27 Claims. (Cl. 62—5)

My invention relates to refrigerators, and more particularly to refrigeration apparatus of the absorption type.

It is an object of my invention to provide a refrigerator of the absorption type which is operated by liquid fuel.

Another object of my invention is to provide an absorption type refrigerator operated by a liquid fuel burner in which the liquid fuel is raised in a path of flow from a supply vessel to the burner.

A further object of my invention is to provide an absorption type refrigerator operated by a liquid fuel burner whereby the normal use and operation of the refrigerator provides energy for causing fuel to flow from a supply vessel to the burner.

A still further object of my invention is to provide an absorption type refrigerator operated by a liquid fuel burner in which liquid fuel is caused to flow by compressed air from a supply vessel to the burner.

A still further object of my invention is to provide an absorption type refrigerator operated by a liquid fuel burner in which fuel is caused to flow from a supply vessel to the burner by the heating effect of the burner flame.

Further objects and advantages of my invention will become apparent from the following description and accompanying drawings, and the various features which characterize my invention are pointed out with particularity in the claims forming a part of this specification.

In the drawings—

Fig. 1 is a side elevation, in section, of a refrigerator embodying my invention; Fig. 2 is an enlarged fragmentary sectional view illustrating more clearly parts of the refrigerator shown in Fig. 1; Fig. 3 diagrammatically illustrates more fully refrigeration apparatus of which parts are shown in Fig. 1; Fig. 4 is an enlarged sectional view of the burner shown in Figs. 1 and 3; Fig. 5 is a fragmentary front view of the refrigerator shown in Fig. 1; Fig. 6 is a modification of the refrigerator illustrated in Fig. 1; Fig. 7 diagrammatically illustrates a further modification of the refrigerator shown in Fig. 1; and Fig. 8 is an enlarged sectional view of the burner shown in Fig. 7.

Referring to Fig. 1, I have shown my invention embodied in a refrigerator including a cabinet 10 having thermally insulated walls 11 defining a storage compartment 12 into which access may be had by a door 13 hinged to the front of the cabinet. Below the storage compartment

part 12 is an apparatus compartment 14 which extends to the rear of the cabinet 10 and communicates with an upward extending compartment 15 which also houses parts of the refrigeration apparatus.

I preferably employ refrigeration apparatus of a uniform pressure absorption type, generally as disclosed in Patent No. 2,063,292 to H. K. Bergholm. Referring to Fig. 3, the refrigeration apparatus includes a generator 16 containing a refrigerant in solution in an absorption liquid. Although I do not wish to be limited thereto, the refrigerant may be ammonia and the absorption liquid may be water. The generator 16 is heated by a liquid fuel burner 17 which projects a flame into the lower conical-shaped end 18 of a flue 19 which extends vertically upward through the generator. A suitable liquid fuel is delivered from a supply vessel 20 through conduit 21, control valve 22 and conduit 23 to the burner 17.

The heat applied to the generator 16 and its contents expels the ammonia out of solution, and the ammonia vapor flows upward to an air-cooled rectifier 24 which condenses water vapor accompanying the ammonia vapor. The water condensed in the rectifier drains back to the generator, and the ammonia vapor flows upward to an air-cooled condenser 25 provided with heat transfer fins 26.

The ammonia is liquefied in the condenser 26 and flows through a conduit 27 to the upper end of an evaporator coil 28 which forms part of the cooling element 29. An inert gas, such as hydrogen, enters the upper end of the evaporator coil 28 from a vertically extending conduit 30. The hydrogen and liquid ammonia are in parallel flow or flowing in the same direction in the presence of each other, and the ammonia evaporates and diffuses into the hydrogen with consequent absorption of heat from the surroundings of the cooling element 29. The resulting gas mixture of ammonia and hydrogen, that is, gas rich in ammonia, flows from the evaporator coil 28 through the outer passage 31 of a gas heat exchanger 32 and vertically extending conduit 33 which communicates at its lower end with the lower end of an absorber 34 about which is arranged a coil 35 through which a suitable cooling medium may be circulated. If desired, the absorber 34 may also be air-cooled in a manner similar to the condenser 25.

The ammonia is absorbed out of the rich gas mixture into weak absorption liquid which enters the upper part of the absorber 34 through a vertically extending conduit 36. The hydrogen,

which is practically insoluble and weak in ammonia, passes upward from the absorber 34 through conduit 37, a plurality of parallel tubes 38 which form the inner passage of the gas heat exchanger 32, and conduit 30 to the upper end of the evaporator coil 28. The gas heat exchanger 32 transfers heat from weak gas flowing to the evaporator coil 28 to the rich gas flowing to the absorber 34.

10 The absorption liquid flowing downward through the absorber 34 in counter-flow to the gas mixture becomes enriched in ammonia by absorption and flows through an inner conduit 39 of a liquid heat exchanger 40 to a coil 41 disposed about the lower end of the flue 19. The rich absorption liquid is raised by vapor-lift action from the coil 41 through conduit 42 into the upper part of the generator 16. The absorption liquid is raised to a higher level in the generator 16 than it is in the absorber 34, and absorption liquid weak in ammonia flows from the lower end of the generator through conduit 43, outer conduit 44 of the liquid heat exchanger 40 and conduit 36 into the upper end of the absorber 34.

15 20 25 30 35 40 45 In order to maintain the cooling element 29 substantially at a desired low temperature, an expansible fluid thermostat responsive to the temperature of the cooling element is arranged to regulate valve 22 and control the flow of liquid fuel to the burner 17. The expansible fluid thermostat contains a volatile fluid and comprises a bulb 45 secured to and in thermal contact with the cooling element 29, an expansible diaphragm 46 communicating with and secured to a hollow member 47, and a conduit 48 connecting the bulb 45 and hollow member 47. The expansible diaphragm 46 and hollow member 47 are arranged to be supported within casing 49 by a resilient diaphragm 50 to which the hollow member 47 is secured. The expansible diaphragm 46 contacts stem 51 of valve 52 which is urged toward its closed position by a resilient spring 53.

When the cooling element 29 tends to rise above the desired temperature, the expansible fluid thermostat causes the expansible diaphragm 46 to expand and move the valve 52 downward against the tension of spring 53 to increase the flow of liquid fuel to the burner 17; and conversely, when the cooling element 29 tends to fall below the desired low temperature the expansible fluid thermostat causes the expansible diaphragm 46 to contract and permit the valve 52 to be urged toward its closed position to decrease the flow of liquid fuel to the burner 17.

55 60 65 70 75 The manner in which parts of the refrigeration just described are arranged in the refrigerator cabinet 10 is clearly shown in Figs. 1 and 5, with similar parts designated by the same reference numerals. The generator 16 is positioned in the vertically extending compartment 15 and arranged within a metal shell 54 which contains a suitable heat insulating material, as indicated at 55. Although not shown in Fig. 1, the condenser 25 and absorber 34 may also be supported in the vertical compartment 15. The gas heat exchanger 32 extends through an opening in a removable wall part 56 of the rear thermally insulated wall, the removable wall part 56 being provided to position the cooling element 29 within the storage compartment 12.

The burner 17 includes a hollow vertical conduit 57 to which is connected the conduit 23. To the upper reduced portion of the conduit 57 is secured a shallow vessel 58 which is adapted

to be filled with alcohol or suitable liquid to provide an auxiliary flame for starting the burner. The upper part of conduit 57 is provided with a pair of forked hollow arms 59 which are closed at their extreme ends. As shown most clearly in Fig. 4, the arms 59 are provided with openings 60 which are in alignment with openings in the lower part of an annular hollow shell 61 which is secured to the outer ends of the arms 59. At right angles to the arms 59 is arranged a U-shaped hollow tube 62 having its ends secured to the shell 61, the tube 62 being provided with openings communicating with openings in the upper part of the hollow shell 61, as indicated at 62a. A small nozzle 63 is provided at the lower part of the tube 62, and above the nozzle 63 is arranged an inverted cup 64 which is provided with a plurality of spaced openings 65 and secured to the inner wall of the annular shell 61.

20 25 30 35 40 45 When the burner 17 is being operated, the liquid fuel in the annular shell 61 is vaporized, and the vaporized fuel flows through the tube 62 and is projected upward in the form of a jet through the nozzle 63. The jet of vaporized fuel, which is mixed with surrounding air within the cup 64, passes through the openings 65 of the cup 64 at which region the burner flame is maintained. The openings 65 in the cup 64 are sufficiently close to the annular shell 61 so that the burner flame will contact the latter and insure vaporization of the liquid fuel in the annular shell 61. To the lower end of the conduit 57 is secured a sleeve 66 which is movable along a rod 67 which is arranged at one side of the apparatus compartment 14 and extends from the front to the rear of the cabinet 10. Suitable means may be provided for pulling the burner 17 forward in the compartment 14 for cleaning and inspecting the burner 17 as well as filling the vessel 58 with alcohol or other suitable liquid for starting the burner. In order that the burner 17 can be moved along the rod 67, the conduit 23 is flexible and provided with a looped portion 68.

50 55 60 65 70 75 The liquid fuel supply vessel 20 is supported by a bracket 69 at one side of the apparatus compartment 14, as shown in Fig. 5, and provided with an air-tight filling cap 70 accessible from the front of the cabinet 10. A door or removable wall (not shown) may be provided at the front of the cabinet to enclose the lower apparatus compartment 14.

The burner 17 is at a higher level than the liquid fuel in the vessel 20, and liquid fuel is pumped to the burner 17 by maintaining the liquid fuel under pressure in the supply vessel 20. This may be accomplished by connecting the supply vessel 20 by means of conduit 71 to the cylinder 72 of an air pump 73 which is located in the storage compartment 12 above the cooling element 29. Within the cylinder 72 is arranged a piston 74 to which is connected a piston rod 75. The piston rod 75 is supported by a bracket 76 and at its forward end is provided with an enlarged head 77 adapted to contact the inside of the door 13 when the latter is in its closed position. When the door 13 is moved from an open to a closed position the rod 75 and piston 74 are moved rearwardly against the tension of spring 78 within the cylinder 72, and the air within the vessel 20 is compressed. When the door 13 is moved from a closed to an open position, spring 78 causes the rod 75 to move forward. During such forward movement of the rod 75, the valve 79 at the inside of the piston 74 opens to admit 75

air into the cylinder 72 which is compressed with the subsequent closing movement of the door 13. A check valve 80 is provided adjacent the air pump 13 to prevent air from flowing from the conduit 71 to the cylinder 72.

Assuming that the pressure within vessel 20 is sufficiently great to pump fuel to the burner 17 and that the valve 20a in conduit 21 is closed, the refrigeration apparatus is started by pulling the burner 17 forward in the apparatus compartment 14 and filling the shallow vessel 58 with a fluid such as alcohol. After igniting the alcohol, the burner 17 is moved back into position below the flue 19 of the generator 16. After the annular shell 61 of the burner has been heated for an interval of time by the auxiliary flame, the valve 20a is gradually opened whereby liquid fuel, such as kerosene, is pumped from the supply vessel 20 to the annular shell 61 of the burner 17. Due to the heating of the annular shell 61 by the auxiliary flame, the liquid fuel is vaporized to provide the burner flame at the openings 65 of the cup 64, as described above. After the burner 17 has been started, the burner flame effectively heats the annular shell 61 to insure vaporization of the liquid fuel.

In view of the fact that the refrigerator door is frequently opened and closed and liquid fuel is consumed at a relatively small rate at the burner 17, difficulty is not generally encountered in maintaining the pressure within supply vessel 20 sufficiently great to pump fuel against the force of gravity from the vessel to the burner. Although the pressure within vessel 20 may fluctuate considerably and hence cause the burner flame to fluctuate in size, the control valve 22 is effective to control the amount of heat applied to the generator 16. When the size of the burner flame is relatively high, for example, the only result is that a greater amount of refrigeration is produced by the cooling element 29 and the thermal bulb 45 is effective to control the valve 22 and reduce the quantity of fuel supplied to the burner 17 sooner than it would if the burner flame were smaller.

Fig. 6 illustrates a modification of the embodiment shown in Fig. 1 in which similar parts are indicated by the same reference numerals. This modification differs from the embodiment just described in that a storage vessel 81 for compressed air is connected in the conduit 71a and the thermal bulb 45 is arranged to control the supply of compressed air from the vessel 81 to the supply vessel 20 by means of a control valve 82 connected to the conduits 71a and 71b.

The control valve 82 includes a casing 83 within which is disposed a valve member 84. The valve member 84 is connected by a rod 85 to an expandable bellows 86. The bulb 45, the expandable bellows 86, and tube 87 connecting the bulb and bellows contain a volatile fluid and constitute an expandable fluid thermostat for moving the valve member 84 in response to the temperature of the cooling element 29. When the cooling element 65 tends to rise above a desired low temperature, the increase in volume of the volatile fluid causes the expandable bellows 86 to expand and move the valve member 84 downward to the position shown in Fig. 6. In this position the passage 87' in valve member 84 communicates with the conduits 71a and 71b and the liquid fuel in the supply vessel is maintained under pressure whereby fuel is pumped to the burner 17.

When the cooling element 29 tends to fall below the desired low temperature, the volatile fluid

becomes reduced in volume and causes the expandable bellows 86 to contract and move the valve member 84 upward. With such upward movement of the valve 84, the conduit 74a is blocked to disconnect the compressed air storage vessel 81 from the fuel supply vessel 20; and, as the passage 87' in the valve 84 moves adjacent to the opening 88 of the casing 83, the supply vessel 20 is opened to the atmosphere and the pressure therein is gradually released so that fuel is no longer pumped to the burner 17.

The control valve 82 and expandable fluid thermostat preferably are so arranged that, when the cooling element 29 is substantially at the desired temperature, the valve 84 assumes such a position that the horizontal portion of the passage 87' is between the connection of the casing 83 to the conduit 71a and the opening 88, whereby the storage vessel 81 is blocked off without completely reducing the pressure in the supply vessel 20. With the storage vessel 81 blocked off, the pressure in the supply vessel 20 gradually becomes smaller as liquid fuel is being pumped to the burner 17 with the result that the burner flame becomes reduced in size. The reduction in size of the burner 25 flame decreases the amount of refrigeration produced by the cooling element 29 and avoids completely shutting off the supply of liquid fuel to the burner 17. Only when the temperature of the cooling element 29 tends to fall below the desired 30 temperature is the valve 84 moved upward such an extent that the passage 87' therein communicates with the opening 88, whereby the pressure in the supply vessel 20 is released and the pumping of the liquid fuel to the burner 17 is 35 stopped.

In order to stop the flow of liquid fuel to the burner 17 when the burner flame is extinguished, I provide a control valve 89 in the conduit 43 which is arranged to be responsive to the temperature of the burner flame. The control valve 89 comprises a casing 90 within which is arranged a valve member 91 which is connected by a rod 92 to an expandable bellows 93. The bellows 93 is connected by means of a tube 94 to a thermal 45 bulb 95 arranged adjacent to the burner 17.

When the burner 17 is being operated, the volatile fluid in the expandable bellows 93 increases in volume and the valve 91 is in the position shown in Fig. 6. In this position the passage 96 of the valve 91 communicates with the conduits 71b and 71c and the supply vessel 20 is in open communication with the storage vessel 81, so that the fuel in the supply vessel 20 is maintained under pressure. In addition, the 55 U-shaped passage 97 of the valve 91 is in open communication with the two parts of the conduit 23 connected to the casing 90, so that the liquid fuel under pressure in the vessel 20 is pumped to the burner 17. If for any reason the 60 burner flame is extinguished, the expandable bellows 93 contracts and the valve 91 is moved toward the right to block off the supply of fuel to the burner 17; and, when the vertical portion of the passage 96 is moved adjacent to the opening 98 in the casing 90, the air under pressure in the supply vessel 20 is discharged to the atmosphere.

The operation of the modification shown in Fig. 6 is similar to that described above in connection with the embodiment shown in Fig. 1, and differs therefrom only in that the bulb 45 is associated with the control valve 82 to regulate the pressure of the liquid fuel in the supply vessel 20, and that the thermal bulb 95 is asso- 75

ciated with the control valve 89 to prevent any overflow of liquid fuel at the burner 17 when the burner flame is extinguished.

Instead of utilizing the opening and closing movements of the door 13 to maintain the liquid fuel in supply vessel 20 under pressure, the air pump may be manually or automatically operable to maintain the liquid fuel under pressure in the supply vessel. By pumping the liquid fuel by compressed air from the supply vessel to the burner, it is possible to locate the supply vessel in the lower part of the apparatus compartment 14 and effect a more desirable arrangement of the refrigeration apparatus in the vertical apparatus compartment 15. Further, in some instances it may be desirable to employ a larger supply vessel which does not require frequent refilling and to locate the same at a distance from the refrigerator. In any case, however, the fact that the liquid fuel is pumped to the burner by compressed air enables the supply vessel to be located below or approximately at the same level as the burner, the pumping of the fuel to the burner being positive and controllable, as described above.

In Fig. 7 I have illustrated a further modification of the embodiments described above in which similar parts are designated by the same reference numerals, it being understood that the parts of the refrigeration apparatus not shown may be arranged in a refrigerator cabinet in a manner similar to that shown in Figs. 1 and 5. In this modification, liquid fuel is pumped from the supply vessel 20' to a higher level by means of the heating effect of the burner 17'. I accomplish this by connecting the conduit 23' from the lower part of the fuel supply vessel 20' to one end of a coil 100 disposed about the lower end of the flue 19, the other end of which is connected by a conduit 101 to the upper part of a vessel 102 located at a higher level than the supply vessel 20'.

The burner 17', which is similar to the burner 17 described above and shown most clearly in Fig. 4, has the forked arms 59' thereof connected by means of a conduit 103 to the lower part of the vessel 102. The upper part of the annular shell 61', to which the ends of the forked arms 59' are secured, is connected by means of a conduit 104 to the upper part of the vessel 102. The supply vessel 20' is provided with an opening 105 adapted to be closed by a valve 106 which may be connected in a suitable manner to be responsive to the temperature of the cooling element 29. This is shown diagrammatically in Fig. 7 by connecting the valve 106 to an expandible bellows 107 which is supported on a bracket 108 mounted on the supply vessel 20'. The expandible bellows 107 is connected by a tube 109 to the bulb 45 which is adapted to be in thermal contact with the cooling element 29, as in the previously described embodiments. The bulb 45, tube 109 and expandible bellows 107 constitute an expandible thermostat containing a volatile fluid which increases and decreases in volume with corresponding changes in temperature.

In the present modification, the refrigeration apparatus is started by heating the lower end of the flue 19 by an auxiliary flame. The auxiliary flame may be obtained by filling the shallow vessel 58' with a suitable fluid, such as alcohol, and igniting the same. The heat applied to the lower end of the flue 19 by the auxiliary flame vaporizes the liquid fuel in the coil 100, thereby causing vapor and liquid fuel to pass up-

ward by vapor-lift action through the small diameter conduit 101 to the vessel 102. The vaporized fuel is conducted from the vessel 102 through the conduit 104, the hollow annular shell 61', and openings 62b into the U-shaped tube 62', and is projected upward through the nozzle 63' into the inverted cup 64' which is secured to the inner wall of the shell 61'. The jet of vaporized fuel, which is mixed with surrounding air, passes through the openings 65' at which region the burner flame is maintained.

The liquid fuel in the vessel 102 is conducted through the conduit 103, forked arms 59' and openings 60' into the annular shell 61'. The liquid fuel is vaporized in the shell 61' due to the heating of the latter by the auxiliary flame, and the fuel thus vaporized mixes with the vaporized fuel conducted through the conduit 104 and also flows into the tube 62' and is projected upward through the nozzle 63'. After the burner 17 has been started, the main burner flame heats the shell 61' to insure vaporization of liquid fuel therein.

If for any reason the main burner flame is extinguished the application of heat to the coil 100 is stopped, and with the cooling of the coil 100 by the surrounding air vaporized and liquid fuel is no longer raised by vapor-lift action from the supply vessel 20' to the vessel 102.

When the cooling element 29 is at the desired temperature, the valve 106 is open and liquid fuel in the supply vessel 20' is at atmospheric pressure during normal operation of the burner, as just described. With the valve 106 open the volatile fluid in the bulb 45, tube 108, and bellows 107 is increased in volume and the valve 106 is in the open position shown in Fig. 7. When the cooling element 29 tends to fall below the desired temperature, the volatile fluid becomes decreased in volume and the expandible bellows 107 contracts, whereby the valve 106 is moved upward to its closed position. With the valve 106 closed the vacuum produced in the supply vessel 20', as the liquid fuel is being pumped therefrom to the vessel 102, renders the burner flame ineffective to raise liquid fuel upward through the conduit 101 into the vessel 102. Although liquid fuel is not being pumped from the supply vessel 20' to the vessel 102, liquid fuel in the coil 100 and the lower part of conduit 101 is vaporized due to the heating effect of the burner flame, and such vaporized fuel is conducted to the vessel 102 and through the conduit 104 to the burner 17'. The liquid fuel burner may be so constructed and arranged that when only vaporized fuel flows to the vessel 102 through the conduit 101, the amount of heat applied to the generator by the burner 17' is reduced sufficiently so that less refrigeration or cold is produced by the cooling element 29 and the latter will tend to remain at the desired temperature.

The vapor lift-action for raising vaporized and liquid fuel in the coil 100 and conduit 101 is readily effected because in most liquid fuels, such as kerosene, constituent parts are present which volatilize at a relatively low temperature. As the quantity of liquid fuel required by the burner 17' is relatively small, a very slight development of vapor is generally sufficient to insure adequate pumping of fuel from the supply vessel 20' to the vessel 102.

In view of the foregoing, it will be understood that I have provided a refrigerator wherein absorption refrigeration apparatus of a uniform pressure type is effectively operated by a liquid

5 fuel burner. Further, the fuel may be caused to flow by compressed air from the supply vessel to the burner by utilizing the opening and closing movements of the door of the cabinet to actuate an air pump, or the fuel may be caused to flow by vapor-lift action due to the heating effect of the burner flame. In the claims, therefore, the words "energy resulting from the operation of said refrigerator for causing flow of fuel" should be interpreted to include energy resulting from any manipulation of the refrigerator or operation of the refrigeration apparatus which is effective to cause flow of fuel from the supply vessel to the burner.

10 15 While I have shown and described several embodiments of my invention, such variations and modifications are contemplated as fall within the true spirit and scope of my invention, as pointed out in the following claims.

What is claimed is:

1. A refrigerator comprising a cabinet having a thermally insulated storage compartment provided with an opening, a door hinged to said cabinet for closing the opening, absorption refrigeration apparatus including a heat receiving part and a cooling element, said cooling element being arranged in thermal exchange relation with said storage compartment, a liquid fuel burner for heating said part, a vessel adapted to contain liquid fuel, means including a conduit for conducting fuel from said vessel to said burner, and means to flow fuel from said vessel to said burner by raising liquid fuel against the force of gravity by energy resulting from operation of said refrigerator.

2. A refrigerator comprising a cabinet having a thermally insulated storage compartment provided with an opening, a door hinged to said cabinet for closing the opening, absorption refrigeration apparatus including a heat receiving part and a cooling element, said cooling element being arranged in thermal exchange relation with said storage compartment, a liquid fuel burner for heating said part, a vessel adapted to contain liquid fuel, means including a conduit for conducting fuel from said vessel to said burner, and means to provide compressed air in said vessel resulting from the operation of said refrigerator for causing liquid fuel to flow from said vessel to said burner.

3. A refrigerator comprising a cabinet having a thermally insulated storage compartment provided with an opening, a door hinged to said cabinet for closing the opening, absorption refrigeration apparatus including a heat receiving part and a cooling element, said cooling element being arranged in thermal exchange relation with said storage compartment, a liquid fuel burner for heating said part, a vessel adapted to contain liquid fuel, means including a conduit for conducting fuel from said vessel to said burner, and means operable by the opening and closing movements of said door to provide compressed air in said vessel for causing liquid fuel to flow therefrom to said burner.

4. A refrigerator comprising a cabinet having a thermally insulated storage compartment provided with an opening, a door for closing the opening, absorption refrigeration apparatus including a heat receiving part and a cooling element, said cooling element being arranged in thermal exchange relation with said storage compartment, a liquid fuel burner for heating said part, a vessel adapted to contain liquid fuel, means including a conduit for conducting fuel

from said vessel to said burner, means to provide compressed air in said vessel for raising liquid fuel against the force of gravity to cause fuel to flow from said vessel to said burner, and means responsive to a temperature condition affected by said cooling element for controlling the flow of fuel from said vessel to said burner.

5. A refrigerator comprising a cabinet having a thermally insulated storage compartment provided with an opening, a door for closing the opening, absorption refrigeration apparatus including a heat receiving part and a cooling element, said cooling element being arranged in thermal exchange relation with said storage compartment, a liquid fuel burner for heating said part, a vessel adapted to contain liquid fuel, means including a conduit for conducting fuel from said vessel to said burner, means to provide compressed air in said vessel for raising liquid fuel against the force of gravity to cause fuel to flow from said vessel to said burner, and means responsive to a temperature condition affected by said cooling element for controlling said last-mentioned means.

6. A refrigerator comprising a cabinet having a thermally insulated storage compartment provided with an opening, a door for closing the opening, absorption refrigeration apparatus including a heat receiving part and a cooling element, said cooling element being arranged in thermal exchange relation with said storage compartment, a liquid fuel burner for heating said part, a vessel adapted to contain liquid fuel, means including a conduit for conducting fuel from said vessel to said burner, means to provide compressed air in said vessel for causing fuel to flow therefrom to said burner, and means responsive to the extinguishment of the flame produced by said burner for discharging the compressed air in said vessel to the atmosphere.

7. In absorption refrigeration apparatus operated by a liquid fuel burner, said apparatus including a cooling element, that improvement which consists in causing fuel to flow from a source of supply to said burner by compressed air, and controlling the compressed air thermostatically in response to a temperature condition affected by said cooling element.

8. In absorption refrigeration apparatus operated by a liquid fuel burner, that improvement which consists in causing fuel to flow from a source of supply to said burner by the heating effect of the burner flame.

9. In a refrigerator, absorption refrigeration apparatus including a heat receiving part and a cooling element, a liquid fuel burner for heating said part, a supply vessel adapted to contain liquid fuel, means for conducting fuel from said supply vessel to said burner, means including a compressed air storage vessel and a conduit connecting said storage vessel and said supply vessel to provide compressed air in said supply vessel for causing liquid fuel to flow from the latter to said burner, a valve in said conduit, and thermostatic means responsive to a temperature condition affected by said cooling element for controlling said valve.

10. In a refrigerator including absorption refrigeration apparatus operated by a liquid fuel burner, that improvement which consists in causing flow of fuel from a source of supply to said burner by raising liquid fuel against the force of gravity by energy resulting from the operation of said refrigerator.

11. In a refrigerator, absorption refrigeration apparatus including a heat receiving part and a cooling element, a liquid fuel burner for heating said part, a supply vessel adapted to contain liquid fuel, means including a first conduit for conducting fuel from said supply vessel to said burner, means including a compressed air storage vessel and a second conduit connecting said storage vessel and said supply vessel for causing fuel to flow from the latter to said burner, means including a valve connected in both of said conduits, and thermostatic means responsive to the extinguishment of the flame produced by said burner for controlling said valve to discharge the compressed air in said supply vessel to the atmosphere and stop the flow of fuel to said burner in said first conduit, a valve in said second conduit, and thermostatic means responsive to a temperature condition affected by said cooling element for controlling said last-mentioned valve.
12. In a refrigerator, absorption refrigeration apparatus including a heat receiving part and a cooling element, a liquid fuel burner for heating said part, a supply vessel adapted to contain liquid fuel, means including a first conduit for conducting fuel from said supply vessel to said burner, means including a compressed air storage vessel and a second conduit connecting said storage vessel and said supply vessel to provide compressed air for causing fuel to flow from said supply vessel to said burner, and means in said second conduit responsive to a temperature condition affected by said cooling element for maintaining said storage vessel in communication with said supply vessel, for disconnecting said storage vessel from said supply vessel, and for discharging the compressed air in said supply vessel to the atmosphere.
13. In a refrigerator, absorption refrigeration apparatus including a heat receiving part and a cooling element, a liquid fuel burner for heating said part, a supply vessel adapted to contain liquid fuel, means including a first conduit for conducting fuel from said supply vessel to said burner, means including a compressed air storage vessel and a second conduit connecting said storage vessel and said supply vessel to provide compressed air in said supply vessel to cause liquid fuel to flow from the latter to said burner, and means responsive to a temperature condition affected by said cooling element for controlling the compressed air in said supply vessel.
14. In a refrigerator, absorption refrigeration apparatus including a generator, a liquid fuel burner for heating said generator, a vessel adapted to contain liquid fuel, means including a conduit for conducting fuel from said vessel to said burner, means including a compressed air storage vessel and a second conduit connecting said storage vessel and said supply vessel to provide compressed air in said supply vessel to cause to flow from the latter to said burner, and means in said second conduit for disconnecting said supply vessel from said storage vessel upon the extinguishment of the flame produced by said burner.
15. In a refrigerator, absorption refrigeration apparatus including a generator, a liquid fuel burner for heating said generator, a vessel adapted to contain liquid fuel, means including a conduit for conducting fuel from said vessel to said burner, and means connected in said conduit adapted to be heated by said burner for causing fuel to flow from said vessel to said burner.
16. In a refrigerator, absorption refrigeration apparatus including a generator, a liquid fuel burner for heating said generator, a supply vessel adapted to contain liquid fuel, a second vessel at a higher level than said supply vessel, means including a conduit for conducting fuel from said supply vessel to said second vessel, means forming a part of said conduit adapted to be heated by said burner for causing vaporized and liquid fuel to flow by vapor lift-action from said supply vessel to said second vessel, and separate conduits connecting said second vessel and said burner for conducting vaporized and liquid fuel, respectively, from said second vessel to said burner.
17. A refrigerator including a cabinet having a thermally insulated storage compartment and apparatus compartments below and at the rear of said storage compartment, absorption refrigeration apparatus including a cooling element arranged in thermal exchange relation with said storage compartment and a generator located in said apparatus compartment at the rear of said storage compartment, a liquid fuel burner for heating said generator located in said lower apparatus compartment below said storage compartment, said burner normally being adjacent to said generator and movable in said lower apparatus compartment to the front of said cabinet, a vessel adapted to contain liquid fuel in said lower apparatus compartment and normally accessible for filling without disturbing said burner, and means including a flexible conduit for conducting liquid fuel from said vessel to said burner.
18. In a refrigerator, absorption refrigeration apparatus including a cooling element and a generator, a liquid fuel burner for heating said generator, a supply vessel having an opening and adapted to contain liquid fuel, a valve for closing said opening, a second vessel at a higher level than said supply vessel, means including a conduit for conducting fuel from said supply vessel to said second vessel, means forming a part of said conduit adapted to be heated by said burner for causing vaporized and liquid fuel to flow by vapor-lift action from said supply vessel to said second vessel when said valve is open, separate conduits connecting said second vessel and said burner for conducting vaporized and liquid fuel, respectively, from said second vessel to said burner, and means responsive to the temperature of said cooling element for closing said valve when said cooling element tends to fall below a desired temperature.
19. In a refrigerator, absorption refrigeration apparatus including a cooling element, a liquid fuel burner for heating said apparatus, a vessel having an opening and adapted to contain liquid fuel, a valve for closing the opening, a conduit for conducting fuel from said vessel to said burner, means connected in said conduit adapted to be heated by said burner for causing fuel to flow from said vessel to said burner, and means responsive to a temperature condition affected by said cooling element for controlling said valve.
20. In a refrigerator, refrigeration apparatus including a heat receiving part, a liquid fuel burner for heating said part, conduit means to conduct liquid fuel from a source of supply to said burner, and means to flow fuel in said conduit means by raising liquid fuel against the force of gravity by energy resulting from operation of the refrigerator.
21. A refrigerator comprising a cabinet having a thermally insulated space provided with an

- opening, a movable closure member for closing the opening, refrigeration apparatus operated by heat and including a heat receiving part and a cooling element, said cooling element being arranged in thermal exchange relation with said space, a liquid fuel burner for heating said part, a supply vessel for liquid fuel, conduit means connecting said vessel and said burner, means to flow fuel from said vessel to said burner by raising liquid fuel against the force of gravity in said conduit means by energy resulting from operation of the refrigerator, and means responsive to a temperature condition affected by said cooling element for controlling flow of fuel in said conduit means.
22. In a refrigerator including refrigeration apparatus having a cooling element and operated by a liquid fuel burner, the improvement which consists in flowing fuel from a source of supply to said burner by raising liquid fuel against the force of gravity by energy resulting from operation of said refrigerator, and thermostatically controlling the raising of liquid against the force of gravity in response to a temperature condition affected by said cooling element.
23. In a refrigerator, refrigeration apparatus operated by heat and including a heat receiving part, a liquid fuel burner for heating said part, a supply vessel for liquid fuel, conduit means connecting said vessel and said burner, means to provide compressed air in said vessel for causing flow of fuel in said conduit means, and means responsive to the temperature of said burner for controlling the compressed air in said vessel.
24. A refrigerator comprising a cabinet having a thermally insulated space provided with an opening, a door for closing the opening, refrigeration apparatus operated by heat and including a heat receiving part and a cooling element, said cooling element being arranged in thermal exchange relation with said space, a liquid fuel burner for heating said part, a supply vessel for liquid fuel, conduit means connecting said vessel and said burner, and means to cause flow of fuel in said conduit means by opening and closing movements of said door.
25. In a refrigerator, a cabinet including a movable member, refrigeration apparatus operated by heat and including a heat receiving part and a cooling element, a liquid fuel burner for heating said part, a supply vessel for liquid fuel, conduit means connecting said vessel and said burner, and means to cause flow of fuel in said conduit means by movement of said movable member.
26. In a refrigerator, absorption refrigeration apparatus including a heat receiving part and a cooling element, a liquid fuel burner for heating said part, a vessel adapted to contain liquid fuel, means including a conduit for conducting fuel from said vessel to said burner, means to provide compressed air in said vessel for raising liquid fuel against the force of gravity to cause fuel to flow from said vessel to said burner, and a valve in said conduit responsive to a temperature condition affected by said cooling element for controlling the flow of fuel from said vessel to said burner.
27. In absorption refrigeration apparatus operated by a liquid fuel burner, said apparatus including a cooling element, that improvement which consists in causing fuel to flow from a source of supply to said burner by compressed air, and releasing the compressed air to the atmosphere upon extinguishment of the burner flame.

GUNNAR GRUBB.
